UNITED STATES PATENT OFFICE.

FRANK DIETRICH WARD AND HARRY CRAMPTON FURNISS, OF HANWELL, ENGLAND, ASSIGNORS OF ONE-THIRD TO HENRY PERCY BRADFORD, OF LONDON, ENGLAND.

INSULATOR FOR THE CONDUCTORS OF ELECTRIC RAILWAYS.

SPECIFICATION forming part of Letters Patent No. 786,472, dated April 4, 1905.

Application filed July 11, 1904. Serial No. 216,162.

To all whom it may concern:

Be it known that we, FRANK DIETRICH WARD and HARRY CRAMPTON FURNISS, subjects of the King of Great Britain, residing at 7 Holly 5 Park Terrace, Church Road, Hanwell, in the county of Middlesex, England, have invented new and useful Improvements in or Connected with Insulators for the Conductors of Electric Railways, of which the following is a specification.

Our invention relates to insulators or insulating supports for the electrical conducting-rails or conductors of surface-contact electric railways.

Hitherto the conducting-rails of electric railways have usually been carried upon insulators cemented or otherwise fixed both to the conducting-rails and to the sleepers of the track. With this arrangement it is found 10 in practice that the depression of the sleepers owing to the passing of a train on the track frequently causes the rupture of such insulators. The object of this invention is to prevent 15 this breakage of the insulators; and to this end our said invention consists, essentially, in the construction of an insulator so that a relative movement or a certain amount of flexibility is provided for between the sleeper carrying the insulator and the conducting-rail upon the insulator.

In a suitable arrangement for carrying out our invention we provide an insulator, of glass or other non-conducting material, the upper surface of which is designed for 20 carrying a clip for attaching the insulator to the rail, while the lower end is adapted to enter a socket, of metal or other suitable material, bolted or otherwise fixed to the sleeper.

To enable our invention to be fully understood, we will describe the same by reference to the accompanying drawings, in which—

Figure 1 is a sectional elevation, and Fig. 2 is a plan, of an insulator constructed according to our invention. Fig. 3 is a section on the line 3 3, Fig. 1. Fig. 4 is a sectional elevation illustrating a modification of the invention.

a is the insulating-block, which is made of glass or other suitable non-conducting mate-

rial and which has preferably embedded in it a reinforcing material, such as wire-netting *b*, 50 to prevent the parts of the block from becoming separated in case of fracture.

c is the clip for carrying the conducting-rail upon the block *a*, and *d* is the socket or base which carries the insulating-block and 55 which is fixed to the sleepers of the track.

The clip *c*, as shown, is provided with two claws *e*, the distance between which is slightly greater than the width of the conducting-rail which the insulator is to carry, but which are 60 so arranged that when the insulator, after being placed under the rail, is turned slightly they will engage with the flange of the said conducting-rail, and so hold the same. It is to be understood, however, that the shape of 65 these claws can be varied according to the particular kind of conducting-rail in connection with which the insulator is used.

The insulator is preferably made of polygonal shape in horizontal section, and the socket 70 *d* is correspondingly shaped, so that when the insulator is in position and the base has been fixed to the sleeper the insulator cannot turn so as to become disengaged from the rail.

In the arrangement of our invention shown 75 in Figs. 1 to 3 the clip *c* is represented as being secured to the upper end of the insulating-block—for instance, by means of cement—as at *f*, and the lower end of the insulating-block is made with vertical sides which fit between the vertical walls *g* of the base, so that the said base shall be free to slide relatively with the insulating-block or the insulating-block relatively with the base without communicating any stress to the said block. In 80 85 the modification illustrated in Fig. 4 this arrangement is reversed—that is to say, the base *d* is adapted to have the insulating-block cemented into it—and the clip *c* is formed with a socket *h*, which fits over and is free to slide 90 upon the upper part of the said insulating-block.

In both of the foregoing arrangements a ledge or lip *i* is provided for preventing the part of the insulating-block which projects 95 into the socket from being wetted. In the ar-

angement shown in Figs. 1, 2, and 3 this ledge or lip is formed upon the insulating-block *a*, and in the arrangement shown in Fig. 4 it is formed upon the clip *c*.

5 Having now particularly described and ascertained the nature of our said invention and in what manner the same is to be performed, we declare that what we claim is—

1. An insulating device for the surface conductors of electric railways comprising among its members, a base having provision for attachment and provided with a socket in its upper face, a cap having provision for attachment to the conductor and provided with a 15 socket on its lower face, and an insulating-block interposed between said base and cap and fitting into both of said sockets, said block being permanently secured in one of said sockets and being free to move vertically in 20 the other of said sockets, substantially as described.

2. An insulating device for the surface conductors of electric railways comprising among its members, a base having provision for attachment and provided with a socket in its 25 upper face, a cap having provision for attachment to the conductor and provided with a socket on its lower face, an insulating-block interposed between said base and cap and fitting into both of said sockets, and means for 30 securing said block to one of said socketed parts, said block being free to move vertically in the other socketed part, substantially as described.

3. In an insulating device for the surface 35 conductors of electric railways, the combination with the base provided with means for attachment and having its upper face provided with a polygonal recess, a cap provided with means for attachment to the conductor, 40 and having a polygonal recess in its lower face, and a block of insulating material polygonal in cross-section fitting said recess, and interposed between the cap and base, said block being permanently secured in one of said recesses and being free to move vertically in the other of said recesses, whereby the cap and base are prevented from turning with respect to each other, substantially as described. 45

4. In an insulating device for the surface 50 conductors of electric railways, the combination with the base provided with means for attachment, and having its upper face provided with a polygonal recess, a cap provided with claws for engaging the foot of the rail, 55 and having a polygonal recess in its lower face, an insulating-block, polygonal in cross-section, fitting in said recesses and interposed between the said cap and base, and permanently secured to one of said parts, said block 60 being provided with laterally - extending flanges extending on all sides beyond the socket portion of said base, substantially as described.
